H. A. SHUNK.

GAS STOVE.

APPLICATION FILED JAN. 2, 1914.

1,209,215

Patented Dec. 19, 1916.

UNITED STATES PATENT OFFICE.

HARRY A. SHUNK, OF BROOKLYN, NEW YORK, ASSIGNOR TO GENERAL GAS APPLIANCE COMPANY, OF NEW YORK, N. Y., A CORPORATION OF NEW JERSEY.

GAS-STOVE.

1,209,215.

Specification of Letters Patent. Patented Dec. 19, 1916.

Application filed January 2, 1914. Serial No. 909,812.

To all whom it may concern:

Be it known that I, HARRY A. SHUNK, a citizen of the United States, residing in the borough of Brooklyn, city of New York, county of Kings, and State of New York, have invented certain new and useful Improvements in Gas-Stoves, of which the following is a specification.

My invention relates to that form of gas stove or range which is provided with two burners, the one located below, and used for heating the oven, and the other located above or in the upper part of the oven and used for broiling and similar operations and particularly to that class of such stoves in which the burners lie at right angles one to the other, the one being supplied with gas from a pipe entering at the front of the stove and the other from a pipe entering at the side of the stove.

A defect in the operation of stoves having two burners has been due to the fact that, while it is not intended that the two burners shall be used simultaneously, it frequently happens that, through inadvertence of the operator, after the gas has been turned on and ignited at one burner, it is turned on at the other with a resulting accumulation and sudden ignition of a considerable quantity of gas with a consequent unpleasant and even dangerous explosive effect. This defect has been remedied in the case of stoves having burners supplied by gas pipes entering on the same face of the stove and consequently having valves located directly one above the other and valve stems running in the same direction, by means of a vertically movable member having parallel projections and corresponding projections on the valve stems by means of which, when one valve is opened the other is locked against opening. Such a construction is not applicable, however, to the case where the gas entrances to the burners are located on different faces of the stove, since it would involve a long run of pipe from one or the other of the gas valves to the corresponding burner with a consequent escape of gas upon the closing of the valve after the burner has been in operation.

The object of my improvement is to remedy this difficulty and to this end my invention consists in providing in combination with controlling valves located in close proximity to the two burners of valve stems

which extend along the two faces of the stove to a common corner thereof and a vertically movable member located at such common corner and having upper and lower lugs projecting therefrom at right angles 60 one to the other and adapted to contact with similarly positioned projections on the two valve stems.

The invention will be best understood by reference to the accompanying drawings, 65 forming a part hereof, Figure 1 of which shows a front elevation, and Fig. 2 a side elevation of a gas stove embodying the same. Fig. 3 shows an enlarged plan view, partly in section, of the stem of the valve which controls the gas supply to the lower stove burner, with its connected parts, and Fig. 4 shows a similar view of the stem of the valve which controls the gas supply to the upper burner with its connected parts. Fig. 5 shows in 70 perspective a portion of the stem of the lower valve provided with a cam or stop and Fig. 6 shows a similar view of the stem of the upper valve.

Referring to the drawings A indicates a 75 gas stove, or range, having upper and lower burners of any ordinary or well known type (not shown in the drawings).

B, is the gas pipe leading to the lower burner and entering at the front of the stove, which is controlled by a valve, C, and B' the gas pipe leading to the upper burner and entering at the side of the stove, which is controlled by a valve, C'. The valves, C, C', are located in close proximity to the burners, 80 and are operated by valve stems, D, D', which, as shown, extend along the two sides of the stove and are prolonged so that they project beyond the faces of the stove along 85 which they lie. Thus the valve stems lie in planes which are at right angles one to the other and intersect one another at the corner of the stove.

At the corner of the stove and movably secured thereto by bolts or pins, e, e, projecting through slots, f, f, therein lies a vertically movable rod or bar, E. The bar, E, is provided near its upper and lower extremities with oppositely faced projecting lugs or shoulders, F, F', which stand at 90 right angles to the other and are adapted to be alternately engaged by similarly positioned projecting cams, or stops, G, G', respectively secured to or forming part of the valve stems, D, D'.

The valves, C, C', are so arranged, in any well known manner, that they can be opened by turning the valve stem in one direction only, in the case shown by rotation to the right.

When it is desired to operate one of the burners, as *e. g.*, the lower one, the valve, C, is opened by turning the valve stem, D, and the cam, G, by pressure against the shoulder,

10. F, raises the bar, E, and brings the shoulder, F', against the stop or cam, G', which is lying in the position it assumes when the valve, C', is closed, so that it is impossible to turn the valve stem, D', to open the valve, C', so long as the lower burner is in operation. In the same manner when it is desired in the first instance to use the upper burner and, for this purpose, the valve, C', is opened the stop, G', is turned down 15 against the shoulder, F', thus holding the shoulder, F, down against the stop or cam, G, so that the valve-stem, D, cannot be turned and thus the valve, C, which controls the pipe leading to the lower burner 20 cannot be opened and this burner cannot be operated. By this means, while the valves are located in close proximity to their respective burners, the opening of the gas-way leading to either burner when the other is in 25 operation is prevented and the simultaneous operation of the two burners is made impossible. If desired the bar, E, may be provided with a shoulder or arm, F², located below the cam, G, whereby, when the valve, C, is closed the bar, E, is moved positively 30 downward by the action of the cam, G. This, however, is not essential as, in case the bar, E, does not fall by gravity, it will, when the valve, C', is opened, be moved downward, so that the shoulder, F, will contact 35 with the cam, G, by the action of the cam, or stop, G', on the shoulder, F'.

I do not claim broadly herein the combination with a gas stove having gas inlets to upper and lower burners on the same side 45 thereof, of means for locking one burner when the other is in operation, nor broadly, the combination with a gas stove of a vertically movable member provided with valve-locking means as these are not of my invention.

What I do claim as new and desire to secure by Letters Patent is:

1. In a gas stove having upper and lower burners and gas inlets thereto through adjacent sides of the stove, the combination of valves for said inlets located in close proximity to the burners, stems for said valves extending along adjacent sides of the stove to a corner thereof, a vertically movable member located at said corner and having upper and lower lugs projecting therefrom at right angles to one another, and corresponding positioned projections upon the valve stems, adapted to make contact respectively with said lugs when the valve stems are turned to open the valves.

2. In a gas stove having upper and lower burners and gas inlets thereto through adjacent sides of the stove, the combination of valves for said inlets located in close proximity to the burners, stems for said valves lying in planes which intersect at a corner of the stove, a vertically movable member lying substantially in the line of intersection 75 of said planes and means operated by the movement of said member for locking one of said burners from operation when the other of said burners is in use.

In testimony whereof, I have hereunto subscribed my name, this 18th day of December, A. D. 1913.

HARRY A. SHUNK.
